DESIGN FOR A WHEEL BALANCING MACHINE

Lee Hunter, Jr., University City, Mo., assignor to
Hunter-Hartman Corp., St. Louis, Mo., a corpo-
ration of Missouri

Application February 1, 1941, Serial No. 98,648

Term of patent 3½ years

To all whom it may concern:

Be it known that I, Lee Hunter, Jr., a citizen of the United States and a resident of University City, in the county of St. Louis and State of Missouri, have invented a new, original, and ornamental Design for a Wheel Balancing Machine, of which the following is a specification, reference being had to the accompanying drawing, forming part thereof.

Fig. 1 is a perspective view of a wheel balancing machine, showing my new design,

Fig. 2 is a plan view of said machine; and

Fig. 3 is a side elevational view of said machine.

I claim:

The ornamental design for a wheel balancing machine, as shown.
